Attorney.

UNITED STATES PATENT OFFICE.

HARRY REGINALD LEYCESTER ETHERINGTON, OF PINNER, ENGLAND.

REAR SIGHT FOR RIFLES AND LIKE SMALL ARMS.

1,425,321.

Specification of Letters Patent.

Patented Aug. 8, 1922.

Application filed January 21, 1922. Serial No. 530,962.

To all whom it may concern:

Be it known that I, HARRY REGINALD LEYCESTER ETHERINGTON, a subject of the King of Great Britain and Ireland, residing at 5 Pinne, in the county of Middlesex, England, have invented certain new and useful Improvements in Rear Sights for Rifles and like Small Arms, of which the following is a specification.

10 This invention relates to improvements in rear sights for rifles and like small arms of the type known as aperture or "peep" sights which comprise a small hole capable of vertical and horizontal adjustment in relation 15 to the barrel of the gun, and it has for its object the provision of improved means for adjusting the position of the aperture forming the sight in which both the size and shape of the aperture can be varied within 20 limits. Another object of the invention is to enable the adjustment of the aperture forming the sight to be performed without varying the position of the element carrying the sighting device relative to the rifle or the 25 like. A still further object of this invention is the production of a sight of the type specified which is of simple construction and which can be manufactured both expeditiously and inexpensively.

30 With the above objects in view the invention consists of certain novel details of construction and combination of parts herein-after fully described and claimed.

In the accompanying drawings illustrating this invention:

Fig. 1 is a front elevation on an enlarged scale of the sighting device.

Fig. 2 is a section on line 2—2 of Figure 1.

Fig. 3 is a front elevation of the main 40 body or casing.

Fig. 4 is a section on line 4—4 of Figure 3.

Fig. 5 is a view in elevation of the inner face of one of the rotary discs.

Fig. 6 is a view in elevation of one of the traversing slides.

Fig. 7 is a view in side elevation of the sight mounted on the stock of a rifle, and

50 Figs. 8 and 9 are diagrammatic views illustrating the position of the near and far rotary discs for given positions of the sighting aperture.

Referring to the drawing in which like parts are denoted by like characters of reference the sighting device comprises a shallow cylindrical member or body part 1 fur-

nished with a centrally disposed diaphragm 2 provided with recesses 3, 4 disposed at right angles to each other one on each side of the diaphragm as particularly shown in 60 Fig. 3. The recesses 3, 4 extend from rim to rim of the casing and are each adapted to receive sliding elements 5, 6 furnished with centrally disposed elongated apertures 7, 8 arranged at right angles to the direction of 65 movement of said slides. The ends of the cylindrical member 1 are closed by means of rotary discs 9, 10, furnished with apertures 11, 12 the centres of which are coincident with the axis of the body part 1. The discs 70 9, 10 are furnished on their inner faces with spiral grooves 13, 14 respectively adapted to receive and coat with pins or projections 16—16 on the parts 5, 6.

By arranging the sliding elements 5 and 75 6 to move at right angles to each other and forming the apertures 7 and 8 of equal widths the aperture or "peep" A is given a square shape. By arranging said elements to move at other angles to one another the 80 aperture or "peep" may be given a rhombic form. Alternatively by making one of the apertures 7 and 8 wider than the other the aperture or "peep" A may be given a rectangular or rhomboidal form, according to 85 the angle at which the elements 5 and 6 slide in relation to each other.

The rotary discs 9, 10 are a revolving fit in the body 1 and the outer rims or edges are milled or otherwise formed as shown at 90 17 to give a grip when it is desired to rotate same to vary the position of the slides 5, 6.

The discs 9, 10 are maintained in position by any suitable means such as a spring clip 95 18 secured at 19 to the body 1, the ends of the clip 18 are provided with lateral projections 20, 21 which are bent over against the faces of the discs, the projections 20 20 being arranged to act as pointers and to co- 100 act with graduations 22 on the discs.

The body 1 is carried by a pillar 23 pivoted at 24 to a base part 25 a spring 26 being provided for maintaining the pillar in position when in use or when folded down 105 against the stock 27 as shown by dotted lines in Figure 7.

In describing the operation of the sight reference is made to the diagrammatic views 8 and 9, the centre part of which in full 110 lines shows the near disc 9, that is, the disc facing the eye, and the outer dotted portion

- represents the graduations on the far disc 10 as it would appear when viewed in the folded down position. Assuming the aperture A to be in the dead centre, and the 5 graduations 9 and 9 on the discs are opposite their respective pointers and further that it is desired to drop the aperture vertically, the disc 9 is rotated in an anti-clockwise direction say until the graduation marked 3 is opposite the pointer 20 as shown in Figure 8, this will have caused the slide 5 to move downwards thereby dropping the slot 7 and consequently the aperture A. If it is desired to raise the aperture A and at the same time to shift same to the left, the disc 9 is rotated in a clockwise direction say until the pointer 20 is opposite the graduation 12 which raises the aperture, and the disc 10 is rotated in an anti-clockwise direction say until the pointer 20 is opposite the graduation 3 which moves the aperture to the left as shown in Figure 9.

It will be appreciated that the aperture 25 A may be moved to any desired position within the area of the apertures 11, 12 in the discs 9, 10 and that a record may be kept of the positions.

The sliding elements 5, 6 may if desired 30 be formed with slots of varying widths and a slide having a slot of one width may be used in combination with a slot of a different width so that the shape of the actual sighting aperture A may be varied as desired.

For the purpose of avoiding frictional contact between the inner faces of the rotary discs 9 and 10 and the outer faces of the sliding elements 5 and 6, the latter are 40 preferably provided with the minutely raised surfaces 28.

What I claim is:—

1. A rear sight for rifles and like small arms comprising a body part fixed to the 45 stock of the rifle against either vertical or lateral movement relative to said stock, a pair of slotted elements adapted to slide at a suitable angle to one another in said body part, and means for imparting a sliding movement to said slotted elements independently of one another.

2. A rear sight for rifles and like small arms comprising a shallow cylindrical member a centrally disposed diaphragm in said 55 cylinder having a transverse recess in each face said recesses being arranged at an angle to one another, apertured elements sliding in said recesses, apertured rotating discs closing the ends of said cylindrical member and interlinking means between said rotating discs and said sliding elements whereby rotary movement of said discs imparts a sliding movement to said sliding elements.

3. In a rear sight for rifles and like small 60 arms the combination of a hinged pillar

adapted to be mounted on the stock of the arm, a cylindrical element carried by said pillar, a pair of apertured sliding elements mounted in said cylindrical element so as to be capable of movement at an angle to one another, two apertured discs each rotatably mounted in said cylindrical element and having a spiral groove in its inner face, and projections on the sliding apertured elements which engage said spiral grooves. 75

4. In a rear sight for rifles and like small arms the combination of a hinged pillar adapted to be mounted on the stock of the arm, a cylindrical element carried by said pillar, a pair of apertured sliding elements 80 mounted in said cylindrical element so as to be capable of movement at right angles to one another, two apertured discs rotatably mounted in said cylindrical element and each having a spiral groove on its inner face, 85 projections on the sliding apertured elements which engage said spiral grooves, and means for maintaining said rotatable discs in position relative to said cylinder.

5. In a rear sight for rifles and like small 90 arms the combination of a pillar adapted to be mounted on the stock of the arm, a cylindrical element carried by said pillar, a pair of apertured elements mounted to slide at an angle to one another in said cylindrical 95 element, two apertured discs rotatably mounted in the ends of said cylindrical element and each having a spiral groove in its inner face, projections on the sliding apertured elements which engage said spiral 100 grooves, means for maintaining said rotatable discs in position relative to said cylindrical element, and means for indicating the positions of said rotatable discs relative to the cylindrical element. 105

6. The combination in a rear sight for rifles and like small arms of a hinged pillar adapted to be mounted on the stock of the arm, a cylinder carried by said pillar, two sliding elements mounted in said cylinder so as to move at right angles to one another, each of said sliding elements having an aperture of rectangular shape, two apertured discs rotatably mounted in said cylinder and each having a spiral groove in its inner face, 110 and projections on the inner faces of the two sliding apertured elements which engage the spiral grooves in the rotatable apertured discs. 115

7. A rear sight for rifles and like small 120 arms comprising a hinged pillar adapted to be mounted on the stock of the arm a cylinder carried by said pillar, two sliding elements mounted in said cylinder so as to move at right angles to one another each of 125 said sliding elements having an aperture of rectangular shape one of said apertures being of greater width than the other, two apertured discs rotatably mounted on said cylinder and each having a spiral groove in 130

its inner face, and projections on the two sliding apertured elements which engage the spiral grooves in the rotatable apertured discs.

- 5 8. The combination in a rear sight for rifles and like small arms of a hinged pillar adapted to be mounted on the stock of the arm, a cylinder carried by said pillar, two sliding elements mounted in said cylinder so as to 25 move at an angle other than a right angle to one another each of said sliding elements having an aperture of rectangular shape one of said apertures being of greater width than the other, two apertured discs rotatably 30 mounted in said cylinder and each having a spiral groove in its inner face, projections on the inner faces of the two sliding apertured elements which engage the spiral grooves in the rotatable apertured discs, and means for indicating the positions of said rotatable discs 35
- 10 so as to move at an angle other than a right angle to one another each of said sliding elements having an aperture of rectangular shape, two apertured discs rotatably mounted in said cylinder and each having a spiral groove in its inner face, projections on the inner faces of the two sliding apertured elements which engage the spiral grooves in the rotatable apertured discs, and means for indicating the positions of said rotatable discs 20 relative to said cylinder.

9. In combination in a rear sight for rifles

and like small arms a hinged pillar adapted to be mounted on the stock of the arm, a cylinder carried by said pillar, two sliding elements mounted in said cylinder so as to 25 move at an angle other than a right angle to one another each of said sliding elements having an aperture of rectangular shape one of said apertures being of greater width than the other, two apertured discs rotatably 30 mounted in said cylinder and each having a spiral groove in its inner face, projections on the inner faces of the two sliding apertured elements which engage the spiral grooves in the rotatable apertured discs, 35 means for maintaining said rotatable discs in position relative to the cylinder in which they are mounted, and means for indicating the positions of said rotatable discs relative to said cylinder.

HARRY REGINALD LEYCESTER ETHERINGTON.
